DESIGN FOR A BRIDGE FOR EYEGLASSES

Henry W. Grom, Rochester, N. Y., assignor to
Arcraft Optical Co., Rochester, N. Y.

Application April 6, 1935, Serial No. 56,244

Term of patent 3½ years

To all whom it may concern:

Be it known that I, Henry W. Grom, a citizen of the United States, residing at Rochester, in the county of Monroe and State of New York, have invented a new, original, and ornamental Design for a Bridge for Eyeglasses, of which the following is a specification, reference being had to the accompanying drawing, forming a part thereof.

Figure 1 is a top plan view of a bridge for eyeglasses showing my new design.

Figure 2 is a front elevation of the same.

Figure 3 is an end elevation thereof.

I claim:

The ornamental design for a bridge for eyeglasses as shown.

HENRY W. GROM.
